PULLEY CLOTHESLINE AND HOLDER THEREFOR

John Waldheim, Elizabeth, N. J.

Application December 5, 1938, Serial No. 243,955

28 Claims. (Cl. 211—119.03)

This invention relates to improvements in pulley clothes line and holders therefor.

The ordinary pulley clothes line has two reaches namely a clothes carrying reach and an idle reach, these reaches move in opposite directions while the line is being operated.

Frequently the articles of clothes are wrapped around both reaches of the line, by the wind, which hinders the operation of the line or in other words makes it difficult to draw in the clothes because of their rubbing action against the idle reach travelling in the opposite direction to that of the clothes carrying reach. The clothes also become soiled by such rubbing action. In some instances this hinderance to the operation of the clothes line has been so great that it has been impossible to draw in the clothes and has necessitated the lowering of the clothes line from the pole in order to remove the clothes therefrom.

An object of this invention is to provide means by the use of which the articles of clothes, if wrapped around the line, do not hinder the operation of the line and do not become soiled.

To this end there is provided means, herein shown, in one form of the invention, as an auxiliary or guard reach, adapted to travel in the same direction as the clothes carrying reach. The guard reach is disposed above the idle reach of the line so that in case the articles of clothes become wrapped around the line they are caused to lie on the guard reach to be held thereby from the idle reach so that said idle reach may move freely in the opposite direction without interference with or hinderance by the clothes, thus making it possible to readily operate the clothes line to pull in the line with the clothes wrapped around it and without soiling the clothes.

In the drawings, which form part of the specification;

Fig. 1 is an elevation of a clothes line in which there are formed four reaches, by a single piece of line, namely a lower or clothes carrying reach, two intermediate or idle reaches and an upper or guard reach;

Fig. 2 is a view similar to Fig. 1, but on a smaller scale, showing a longer clothes line and the use of a plurality of holders to maintain the reaches of the clothes line in proper relation and definitely spaced from each other;

Fig. 3 is a view similar to Fig. 2 but shows a different arrangement of holders;

Fig. 4 shows one end of the novel clothes line and still another arrangement of holders;

Fig. 5 is an end view of one of the pulley brackets;

Fig. 6 is a sectional view taken on the line 6—6 of Fig. 1;

Figs. 7 and 8 are front and end elevations, respectively, of the kind of holder used on the type of clothes line having four reaches;

Fig. 9 is a horizontal section taken on the line 9—9 of Fig. 7;

Figs. 10 and 11 are front and end elevations, respectively, of a type of holder used as illustrated in Figs. 3 and 4;

Fig. 12 shows another form of four reach clothes line and in which the intermediate reaches are located closer to the guard reach;

Figs. 13 and 14 are front and end elevations, respectively, of a holder used to maintain the reaches as spaced in Fig. 12;

Fig. 15 shows a four reach clothes line in which the two intermediate reaches are formed differently to those in Fig. 2 and in which they are located close to the guard reach;

Fig. 16 is similar to Fig. 15 but shows the lower reach shifted outwardly towards the pole supported end of the clothes line and a plurality of holders attached;

Fig. 17 shows a clothes line having only three reaches;

Fig. 18 is similar to Fig. 17 but shows the lower reach shifted and a plurality of holders attached;

Fig. 19 shows one end of a clothes line similar to that shown in Fig. 17 but illustrating another method of attaching one end of the guard line;

Figs. 20 and 21 are views similar to Figs. 17 and 18 and show a four reach clothes line in which the guard reach and one of the intermediate reaches are formed by a separate piece of clothes line;

Figs. 22, 23 and 24 are front, end and plan views, respectively, of an end holder which may be used on the clothes line shown in Figs. 17 to 20;

Figs. 25 and 26 are front and plan views, respectively, of a form of detachable holder which may be used on the clothes lines shown in Figs. 17 to 21;

Fig. 27 is an end view of the upper portion of the holder shown in Fig. 25;

Fig. 28 is an elevation of a clamp for securing one end of the guard reach in the form of clothes line shown in Figs. 17 and 18;

Fig. 29 is a vertical section taken on the line 29—29 of Fig. 28;

Fig. 30 is an elevation of a link used in the clothes line shown in Figs. 15 and 16;

Fig. 31 is a plan view of the link shown in Fig. 30;

Fig. 32 is an elevation of a portion of a three reach clothes line with another type of holder;

Fig. 33 is a top plan view of the upper end of the holder shown in Fig. 32;

Fig. 34 is a bottom plan view of the holder shown in Fig. 32;

Fig. 35 is a vertical section taken on the line 35-35 of Fig. 32;

Fig. 36 is a side elevation of a two reach clothes line with, means including a modified form of 10 guard applied thereto;

Fig. 37 is an enlarged view of the holder used in Fig. 36;

Fig. 38 is an end view of Fig. 36;

Fig. 39 is a top plan view of Fig. 36;

Fig. 40 is an elevation of one of the rod units used in Fig. 36;

Fig. 41 is a vertical section taken on the line 41-41 of Fig. 40; and

Fig. 42 is a view showing a fragmentary portion of the rod unit illustrated in Fig. 40 and shows the rod expanded to its longest position.

Similar reference characters represent similar parts throughout the specification.

In Figs. 1 and 2 the clothes line is indicated generally by the numeral 29 and is supported by pulley brackets 30 and 31 between a building 32 and a pole 33. The clothes line in this form of the invention is composed of a single piece of line or rope arranged to provide four reaches, 30 namely a lower or clothes carrying reach 34, two idle or intermediate reaches 35 and 36, and an upper or guard reach 37, these reaches being formed in the following manner. The lower reach 34 of the line extends around a pulley 38, 35 of the bracket 30, to form the intermediate section 35 which extends from the upper part of the pulley 38 to the lower part of a pulley 39 on the block 31 at the opposite end of the clothes line 29. The reach 35 extends around the pulley 39 40 and merges with the guard section 37 which extends from the upper part of the pulley 39 to the upper part of a pulley 40 of the bracket 30. The piece of line then passes around the pulley 40 to form the intermediate reach 36 which extends from the lower part of the pulley 40 to the upper part of a pulley 41 on the bracket 31. The piece of line finally passes around the pulley 41 and forms the lower reach 34. In thus passing around the pulleys 38, 39, 40 and 41 the piece of line forms a flat figure 8, and consequently the two intermediate or idle reaches 35 and 36 travel in the same direction and opposite to the direction of travel of the outer reaches 34 and 37.

Therefore if the pieces of clothes 42, carried by the lower reach 34, and attached thereto in the usual manner, are blown over the entire clothes line, as in Figs. 1 and 6, they are caused to lie on the upper or guard reach 37 which prevents them from resting upon the intermediate reaches 35 and 36. Consequently since the guard reach 37 upon which the clothes rest, always travels in the same direction as the clothes carrying reach 34 the line may be operated readily without hinderance by the clothes to draw them in and without soiling them.

The pulley brackets 30 and 31 comprise each a vertically disposed, flat O-shaped member 45, Figs. 1 and 5, through which extend spindles 46 for the pulleys, and a horizontally disposed U-shaped member 47 the free ends of which may be secured to the sides of the O-shaped member in any convenient manner. The closed ends of the U-shaped members 47 engage hooks 48 and 49 on the building 32 and pole 33 respectively.

Provision is made to tighten or slacken all of the reaches 34, 35, 36 and 37, of the line 29, simultaneously. To this end the rope which constitutes the four reaches has a loop 50 formed thereon, at one end, through which the other end 51 may slip freely while drawing the reaches tight or slackening them as desired. Subsequently any suitable knot 52 may be made to prevent accidental slipping of the end 51 through the loop 50. The tightening or slackening of the line may also be accomplished independent of the loop 50 by a special device 51x which may be like that shown, described and claimed in my copending application, Ser. No. 243,956 filed, of 15 even date, December 5, 1938.

To maintain the reaches 34, 35, 36 and 37 of the clothes line in their proper relation and definitely spaced from each other, when the clothes line is long, as in Fig. 2, there are provided means including one or more supports or holders 55, one form of which is shown diagrammatically in Fig. 2.

The holder 55 is illustrated in detail in Figs. 7, 8, and 9, and several may be used on a long clothes line. They may readily be attached at intervals to the clothes line as the hanging of the articles of clothes 42, on the reach 34, proceeds. Each holder 55 comprises a body part 56 having two stationary, cantilever spindles 57 secured thereto. Rollers 58 are mounted to run on the spindles 57 and cooperate with the intermediate reaches 35 and 36. These rollers may be composed of wood or other fibrous material and are therefore provided with bushings 59 to prevent rapid wear of said rollers on the spindles 57.

The rollers 58 are offset with respect to each other, as seen in Fig. 7, so as to provide a diagonally disposed slot or passage way 59 between them through which the intermediate reaches 35 and 36 of the clothes line may be inserted or removed only when the holder and reaches 35 and 36 are placed diagonally with reference to each other so that the passage way 59 is substantially parallel with the nearest portions of the intermediate reaches 35 and 36. After the reaches 35 and 36 have been placed between the rollers 58 and the holder has returned to a vertical position with reference to the reaches 34 and 37 it may be attached at its opposite ends to the lower and upper reaches 34 and 37, respectively. It will be seen that in this vertical position of the holder 55 the flanges 60 of the rollers 58 overlap each other as seen in Fig. 8, and overlap the intermediate reaches 35 and 36, as seen in Fig. 7, to thus prevent accidental detachment of the holder from said intermediate reaches or vice-versa.

To attach each holder 55 to the outer reaches 60 34 and 37 its body part 56 is provided with hook-like attaching means 61 and 62. The hook-like means 61, in this form of holder, comprises two up turned hooks 63 which extend to one side of the body part 56 so that the reach 34 may readily be inserted into said hook-like means from one side of the holder. The hooks 63 are angularly disposed with reference to each other so as to present corners 64 and 65 to form a bight 66 in the reach 34 to thereby grip the reach 34 tightly and cause the holder to travel therewith.

To prevent accidental detachment of the holder 55 from the reach 34, there are provided two obstructing or guard members 67 associated with the hook-like means and which, in the present 75 form of the invention, are located one on the

upper end of each hook 63. These guard members extend diagonally over the reach 34 to prevent accidental removal of the reach 34 from the hooks 63 and thus accidental detachment of the holder from the line is prevented.

To attach the holder 55 to the reach 34 the latter may first be placed in one of the hooks 63 and under the guard 67 by placing said holder diagonally with reference to the reach 34. The holder may then be brought to a vertical position and the other part of the reach 34 may now be readily pushed down over the incline face 68 of the guard member 67 on the other hook 63 until it snaps under the guard member 67. To remove the holder 55 from the reach 34 the latter is bent back at one side of the holder and towards the body part 56 thereof until it clears the guard 67. The reach may then be lifted out of one of the hooks 63. Subsequently the holder may be turned slightly about its vertical axis until the other guard member 67 clears that portion of the reach in the other hook 63. The holder is then moved downwardly from the reach 34.

The hook-like means 62, at the upper end of the holder 55, is the same and functions similarly to the hook-like means 61 and the corresponding parts have the same reference characters applied thereto, the only difference being that the hooks 63 at the upper end are downturned to hook on to the reach 37 and the guard members 67 extends under the reach 37 to prevent accidental detachment of the holder from said reach. It is immaterial whether the holder is first attached to the lower reach 34 or upper reach 37. In any event, however, the holder should be brought to a vertical position before it is attached to the second outer reach.

All of the corners which come in contact with the reaches 34, 35, and 37, such as the side edges of the body part and the corners 64, 65 and others, are slightly rounded so as to prevent cutting of the line reaches thereby. This is also true of all of the other holders herein described.

From the above it will be understood that each holder 55 hangs on the upper reach 37 by its hook-like means 62 and is supported on the intermediate reaches 35 and 36 through the upper one of its rollers 58, and that the lower reach 34 is supported by the holder through the medium of the hook-like means 61. It will further be understood that the holders 55 are secured to the outer reaches 34 and 37, and that they not only prevent the spreading of the outer reaches 34 and 37 with reference to each other and with reference to the intermediate or idle reaches, but because of the guard members 68, they also prevent movement of said reaches towards each other, which may otherwise be caused by the clothes when tightly wrapped about the clothes line. It will also be understood that as many holders may be used on a clothes line as are found necessary in accordance with the length of said clothes line. It will be understood that without the use of one or more holders, of the present invention, on a pulley line of considerable length, the guard reach would be insufficient to hold the clothes from the idle reach to prevent the objectionable rubbing action of the clothes against said idle reach.

The holder 55 is symmetrical in construction and therefore it is not necessary to determine which end should be attached to the upper reach of the line. In other words either end of the holder may be applied to one of the outer reaches

and the opposite end may then be applied to the other outer reach. Accordingly either one of the rollers 58 is capable of running on the intermediate reaches 35 and 36 while the other roller, located under the reaches 35 and 36 serves only as a guard to assist in preventing accidental detachment of the intermediate reaches 35 and 36 from the holder.

Instead of the holder 55 the type indicated by the numeral 70, Figs. 10 and 11 may be used in the manner indicated diagrammatically in Fig. 4. It will be noticed that the holder 70 has only one roller 58a which is supported on a spindle 57a and runs on the intermediate reaches 35 and 36. The flange 60a of the roller 58a cooperates with a guard member or finger 71 to prevent accidental detachment of the holder 70 from the intermediate reaches. To attach the holder 70 to or detach it from the intermediate reaches 35 and 36 it must be placed diagonally with reference to said intermediate reaches so that said reaches may be passed through the passage way 59a formed by the flange 60a and the guard member or finger 71. The finger 71 may be struck up from the body part 56a and extends forwardly therefrom. It is located in a horizontal plane sufficiently close to the lower portion of the flange 60a to prevent detachment of the reaches 35 and 36 from the roller 58a while the holder is in a vertical position.

To attach the holder 70 to the lower or clothes supporting reach 34, it is provided with hook-like means 61a the construction of which is identical with that of the hook-like means 61 of the holder 55 shown in Fig. 7, corresponding parts being identified by the same reference characters with the addition of the letter *a*.

The holders 70, are used in pairs, one of each pair being applied, as above described, to run on the intermediate reaches 35 and 36 by which it is supported, and to support the clothes carrying reaches 34. The other holder 70 of the pair is inverted as in Fig. 4, and is applied to and hangs from the upper reach 37 through the medium of the attaching means 61a. It is located close to the other holder 70 and the roller 58a thereof engages under the intermediate reaches to support them.

These holders 70 may be used in pairs instead of each holder 55 as above mentioned, or they may be used individually with the holders 55 as illustrated in Fig. 3, where they are located between the holders 55. The holder 70 may also be used to a good advantage on an ordinary two reach clothes line for the purpose of holding said reaches together, and without the possibility of accidental detachment from either reach of the clothes line. When the holder 70 is so used the groove in its roller 58a may be sufficiently narrow to accommodate only one reach of the clothes line.

In the clothes line 29b the intermediate reaches 35 and 36 may be located close to the upper reach 37 as illustrated in Figs. 12, 13 and 14. For this purpose the pulleys 38b and 40b and the pulleys 39b and 41b may be staggered with reference to each other in their brackets 47b, and the type of holder which may be used on this clothes line is indicated generally by the character 75.

The holder 75 is, in some respects, like the holder 70 of Fig. 10 since it has a similar roller 58b, mounted on a spindle 57b to run on the intermediate reaches 35b and 36b of the line 29b. It also has a guard or finger 71b cooperating with a flange 60b of roller 58b to prevent

accidental detachment of the holder 75 from the intermediate reaches 35b and 36b. At its lower end, the holder 75 is provided with hook-like attaching means 61b which is also like that of the holder 70 and supports the lower reach 34b of the clothes line. The holder 75 also resembles the holder 55 since it is provided, at its upper end, with a hook-like means 62b to hang on the upper reach 37b. This hook-like means 62b is formed by a single lip 63b bent from the body part 56b to form an inverted groove 76 in which the upper reach 37b of the clothes line 29b engages.

The free end of the lip 63b is provided with guard members 77 which extend downwardly towards the flange 60b of roller 58b and cooperate therewith to prevent accidental detachment of the holder from the reach 37. To detach the holder from the line the reach 37 may be bent or the upper end of the holder 75, which is free to slide on the reach 37, may be moved to one side in the direction of the reach, sidewise in Fig. 13, until the reach 37b clears one of the members 77, in order that the reach may be moved through the passage way 78, formed by the members 77 and the flange 60b of the roller 58b. After thus removing the reach 37b at one side of the holder the upper end of said holder may be moved to the opposite side in Fig. 13 to complete the removal of the reach 37b from said holder.

It will be understood that in the holder 75 only the hook-like means 61b grips the clothes line, the hook-like means 63b at the upper end simply hangs on the reach 37b but does not grip it, therefore the holder may shift slightly, if necessary, relatively to the reach 37b, thus permitting said holder or holders to remain vertically disposed with reference to the line in case the tightening thereof is effected after the holders 75 have been attached. Said tightening, it will be remembered, may be effected by the special device 51x. When the special device 51x is used the tightening may be effected after the clothes are hung on the line and it is then that the upper reach 37b shifts slightly relatively to the upper ends of the holders 75.

In Figs. 15 and 16 there is illustrated another form of clothes line indicated generally by the reference character 29c and having four reaches 34c, 35c, 36c and 37c. In this form of the invention the line is supported by two large pulleys 38c and 41c and two small pulleys 39c and 40c, each pair of pulleys at the opposite ends of the line being supported in a suitable bracket, not shown, to suspend the clothes line between suitable supports, such as a building and a pole, the smaller and larger pulleys being used instead of the staggered pulleys of the same size, shown in Fig. 12, to cause the intermediate reaches 35c and 36c to be located closer to the guard reach 37c.

The reaches 34c, 35c, 36c and 37c are of the clothes line 29c are also formed of a single piece of rope, but the intermediate sections 35c and 36c do not extend directly from one end to the opposite end of the clothes line but each reach is composed of two sections which extend towards each other to form loops 80x in which engage rollers 80 of a link 81 to thus connect said intermediate sections.

All of the reaches 34c, 35c, 36c and 37c of the clothes line 29c may be tightened or slackened, simultaneously, and also secured, similarly to

those of the line 29 of Fig. 1, by means of a loop 50c and a knot 52c.

The link 81, as herein illustrated, see Figs. 30 and 31, is composed of two plates 82 separated from each other by shouldered rivets 83 upon which the pulleys 80 are mounted to rotate freely. The ends 84 of the plates 82 are bent in so far to facilitate its passage through a holder 85, Fig. 25.

10 The holder 85, which is used on the clothes line 29c of Figs. 15 and 16, is illustrated in Figs. 25, 26 and 27 and is similar to the holder 75, shown in Figs. 13 and 14, since it is provided with a roller 58c supported by a headed spindle 51c secured to the body part 56c and because the lower end of the body part is provided with hook-like means 61c, like that shown in Figs. 7 and 13, which grips the reach 34c to cause said holder 85 to travel with said reach.

20 The hook-like means 62c at the upper end of the holder 85 is also similar to that of holder 75 since it does not grip the reach 37c to permit slight freedom of movement between the holder and the reach 37c. It differs in construction, 25 from that of holder 75, however, in that the hook 63c is formed at the upper end of a narrow portion 86 of the body part 56c. A further distinction of the construction of the holder 85 over that of holder 75, is that the guard members 77c do not cooperate with the flange 60c of the roller 58c, but with the narrow portion 86, to prevent accidental detachment of the holder from the guard reach 37c, said guard members 77c extending diagonally rearward under the reach 37c.

30 Thus it is impossible to remove the reach, while in straight condition, from the hook 63c. In order to remove it, it is necessary to angularly dispose the reach and holder with reference to each other, as viewed from the top, Fig. 26, until the reach 37c clears the free end of the member 77c whence the reach may be moved downwardly at one side of the holder, out of the hook 63c. This operation is then repeated at the opposite side of the holder to completely remove the reach 37c from said holder.

35 The intermediate reaches 35c and 36c are guarded against accidental detachment, from the holder 85, by the guard finger 71c which extends upwardly to overlapping relation with respect to the flange 60c of the roller 58c as viewed from the right hand side of Fig. 25. The finger 71c forms with the roller flange 60c a passageway 59c through which the intermediate reaches may be passed, for the purpose of attaching or detaching, only when the holder and the pair of reaches are angularly disposed with respect to each other in a vertical plane in which the clothes line is disposed.

40 There is a natural tendency for the link 81 to remain vertical on the line, as in Figs. 15 and 30, and provision is made to facilitate its passage through the holder 85, one or more of which may be used on the clothes line 29c. To this end the ends of the plates 82, as previously stated, 45 have their ends 84 bent inwardly, as shown in Figs. 30 and 31, to prevent catching on the edges of the body part 56c, the edge of the guard finger 71 and the side edges of the body part 56c. The opposite side edges of the body part 56c are also provided, for this purpose, with outwardly and rearwardly extending lips 87 and 88 which may be of any suitable length.

45 The invention may also be applied to an already existing two reach clothes line by supplying only enough new rope to provide the guard

reach thus keeping at a minimum the immediate cost of material in applying the invention. For this purpose provision is made, see Figs. 17 and 18, of a guard line 37d which is formed of a separate piece 89 of rope applied to the already existing clothes line supported by two pulleys 90, and having two reaches, namely the clothes carrying reach 34d and the idle reach 35d. The separate piece 89 of rope or line may be attached by securing one end thereof to a specially formed loop 91 in the lower reach 34d, the loop 91 being formed far enough from the loop 59d to never pass through the latter loop while tightening the reaches of the line 29d. The piece 89 of line extends from said loop through a holder 92, indicated diagrammatically in Figs. 17 and 18, but shown clearly in Figs. 22, 23 and 24, and which is secured to the clothes supporting reach 34d, as hereinafter described. The piece 89 of rope then extends from the upper part of the bracket 92 to a pulley 39d which may, if desired, be supported by a separate bracket independently of the pulley 90. The piece 89 of rope passes over and around the pulley 39d and extends to the opposite end of the clothes line 29d where its other end may be secured to reach 35d by a clamp 93 illustrated in Figs. 28 and 29.

The loop 50e, in the lower reach 34d, which forms part of the means for loosening or tightening all the reaches of the line 29d, may be formed as at 51e, Fig. 19, in which the loop and that end of rope which slides through it are arranged in reverse order to that shown in Fig. 17 and the end of the portion 89 may be secured directly to said loop. In this arrangement the formation of a special loop, 91, such as shown in Fig. 17, is avoided and the end of the rope 89 is secured to the already existing loop 50e. It should be understood also that instead of attaching the end of the line portion 89 to the clothes carrying reach 34d by means of loops 91 or 50e it may be secured to said reach by means of a clamp such as 93 shown in Fig. 28.

It will be understood that the piece of rope 89 constituting the guard reach 37d may also be applied to the line, if desired, by first attaching it by means of the clamp 93 and then attaching it at the loop 91. In any event the reaches 34d and 35d are first tightened by means of the loop 50d and knot 51d before securing the last end of the rope 89. Thus the guard section 37d, which remains permanently attached as part of the line 29d, may readily be loosened or tightened simultaneously with the other reaches 34d and 35d.

Only one holder 92 illustrated in Figs. 21, 22, 23 and 24 is used on the clothes line shown in Figs. 17 and 18. This holder is similar to the holder 85 shown in Fig. 25. Instead of the hook-like securing means 61c, however it is provided at its lower end with securing means in the form of a clamp 61d comprising a fixed jaw 95, formed integral with the body part 56d, and a jaw 96 of a movable plate 96x. The body-part 56d has a horizontal groove 97 in which a lip 98 of the jaw 96 engages, and about which the jaw 96 may be swung to adjust it properly to the other jaw 95 to clamp or release the reach 34d.

The clamp 61d may be operated, to grip the reach 34d tightly, by means of a thumb screw 99 having a shank 100 which extends freely through the jaw plate 96x and is threaded into the body part 56d. The free end of the shank 100 is provided with an annular rib 101 to prevent detachment of the clamp plate 96x and 75

thumb screw 100 and thus avoid possible loss of these parts. The jaw 95 is knurled at 102, and also the jaw 96, to assist in gripping the reach 34d.

The holder 92 is provided, at its upper end, with securing means 62d comprising two outer fingers 103 and a middle finger 104. These fingers are arranged to form a bight 104, in the line portion 89, as shown in Fig. 24. Thus the upper end of the holder 92 is held firmly and kept from shifting leftwardly, at its upper end, in Figs. 18 and 22. The holder 92 is also provided with a roller 58d which is supported on a spindle 57d and runs on the reach 36d. A guard finger 11d is also provided on the holder 92 to cooperate with the flange 60d of the roller 58d to prevent accidental detachment of the holder from the reaches 35d and 36d. Lips 87d and 88d are also provided at the opposite side edges of the body part 56d to facilitate the passage of the clamp 93 through the holder 92.

The clamp 93, by which the end of the rope 89 is secured to the reach 35d, is clearly illustrated in Figs. 28 and 29 and is composed of two oppositely disposed plates 105 and 106 having knurled grooves 107 and 108 to embrace the reach 35d and end of the rope or line section 89. Said plates may be drawn together by screws 109 to tightly grip the rope 89 and reach 35d, the shanks of said screws passing freely through the plate 105 and being threaded into the other plate 106.

To further facilitate the passage of the clamp 93 through the holder 92 there is provided on one of its plates 95 and 96 an inclined tail 110 which readily guides the clamp 93 under the roller 58d when the clamp passes the roller from the left side in Fig. 22. The opposite edges of each plate 105 and 106 may also be provided with projections 111 which are also bent inwardly from each plate and towards each other like the ends 84 of the link 84. The edge portions, of each of the plates 105 and 106, above and below the projections 111 are rounded to further facilitate passage of the clamp 93 through the holder 92.

Another form of holder, 115, illustrated in Figs. 32 to 35 inclusive, may be used instead of the holder 92 shown in Fig. 22. This holder 115 is provided at its upper end with an aperture for the purpose of securing thereto one end of the reach 37d instead of securing it to the lower reach 34d as shown in Fig. 18. A roller 58f rotates in a spindle 59f secured to the body part 56f of said holder, the flange 60f of said roller cooperating with a guard finger 11f to prevent accidental detachment of the holder from the reach 35d. The lower reach 34d by means of a clamp 61f which is similar to the clamp 61d except that the jaws 95f and 96f are held together by two machine screws 99f.

The tendency of the guard reach 37d is to pull the upper end of the holder 115 leftwardly in Fig. 32. This tendency is counteracted by an arm 117 extending from one side of the holder and along the reach 34d to which the distal end of said arm may be attached in any suitable manner. As herein illustrated the arm 117 is L-shaped and forms part of the clamp jaw 95f, and to facilitate attachment thereof to the reach 34d it is provided with an elongated slot 118 through which the reach 34d extends diagonally as shown in Fig. 34, the reach 34d being insertable into said slot through a narrow passage 119. Thus it will be understood that as the guard reach 37d pulls leftwardly on the upper end of the holder

115 the distal end of the arm 117 pressed downwardly against the reach 34d to counteract the tendency of the guard reach and thus the holder 115 is maintained in a substantially vertical position by the arm 117 acting against the reach 34d. It will be understood from Fig. 32 that the slot 118 and narrow passage 119 form guard members 119x to prevent accidental detachment of the distal end of the arm 117 from the reach 34d.

From the foregoing it will be understood that there is provided, by the additional piece 89 of line, an extra pulley 39d and a holder such as 92 or 115, a three reach clothes line including a guard reach 37d to prevent the clothes from rubbing on the idle reach 35d of the clothes line, and that in the event that the clothes line is long additional holders 85 may be attached thereto, as shown in Fig. 18, as the operation of the line proceeds in hanging out the clothes.

By employing a longer portion 89g of rope, as shown on the clothes line 29g, illustrated in Figs. 20 and 21, the use of clamp 93 such as used on the clothes line 29d, Fig. 17, may be avoided, and detachable holders 85, as shown in Fig. 25, may be used. In this form of clothes line the extra portion 89 of rope which forms the guard reach 37g, is long enough to extend around the pulley 90, at the right in Figs. 20 and 21, in all possible positions of the clothes line and never passes any of the holders 75 and 92.

Thus the clothes line 29g, has four reaches 34g, 35g, 36g and 37g, two of the reaches 34g and 35g constituting the two reaches of an ordinary clothes line, the two additional reaches, 36g and 37g, being provided by means of the separate piece 89g of rope which is supplied principally to form the guard reach 37g to prevent the clothes from rubbing against the intermediate reaches 35g travelling in a direction opposite to the clothes supporting reach 37g and said guard reach.

It will be understood that light articles such as hankerchiefs and towels may be hung, if desired, from the uppermost reach of the clothes line. If the clothes line is so used or otherwise the holders or separators 55 or 75 and the taut condition of the clothes line between the separators prevent sagging of the upper reach, under the weight of the clothes which may be hung therefrom, and thus prevent bearing down and rubbing on the intermediate reaches.

Another advantage of the holders 55 and 85 is that they cause the loads, which may be supported by the upper and lower reaches, to be partially borne by the intermediate reaches.

In the form of the invention shown in Figs. 36 to 42 inclusive the pulley line 29p is composed of only two reaches as the one shown in Fig. 32, namely a clothes carrying reach 34p and an idle reach 35p. The clothes line 29p is supported at opposite ends by pulleys 90p around which it runs freely. In this form of the invention there is provided a plurality of holders 160 each having means 61p at its lower end whereby the holders may be attached to the clothes carrying reach 34p. Each holder 160 is further provided with two supporting rollers 58p to embrace the idle reach 35p to keep the two reaches close together. The idle reach 34p assists in maintaining the holder in upright positions.

A guard roller 71p is also provided beneath the reach 35p to cooperate with the rollers 71p to prevent accidental detachment of the holder from the reach 35p of the line. To attach the

holder 160 to the idle reach 35p the latter is passed through the spaces 59p formed by the rollers 58p and roller 59p.

In this form of the invention the guard means, which prevents the article of clothes from lying on the idle reach 35, consists of bars 37p extending from one holder 160 to the next as shown in Fig. 36.

The bars 37p are detachably mounted on the 10 holders 160. To this end each rod has at its end, downwardly extending portions 161, the free end 162 of each portion 161 being tapered so that it may be readily be inserted into an aperture 163 of the holder 160.

15 Each rod 37p is adjustable lengthwise so that it may be expanded in accordance with the distance between two holders and so that it may be collapsed to occupy a minimum of space while storing. For this purpose each rod is composed 20 of two members 164 and 165, the member 164 being provided at one end with an eye 166 which embraces the member 165 and through which it may slide freely. The rod member 165 is also provided with an eye 167 which similarly embraces the rod member 164.

25 Provision is made to prevent sagging of the rod 37p at the middle thereof when it is in its extended position, a stop 168 being provided on the member 165 which engages the eye 166 as 30 shown in Fig. 42 so that the eye 167 is far enough from the eye 168, while the rod is expanded to its maximum length, to prevent sagging of the rod.

To retain the rods 37p on the holders 160, or in 35 other words prevent accidental detachment therefrom, each holder has formed thereon at its upper end two adjacent retaining members 169, each retaining member being composed of a back portion 170 extending upwardly from the 40 body part 56p of the holder, a horizontal portion 171 extending from the back portion 170 and a tongue 172 extending downwardly from the horizontal portion 171. A detent 173 may be provided in the back portion 170, and a similar detent 174, formed on the lower end of the tongue 172, engage in an annular groove 175 formed 45 above the tapered end 162 of the end portion 161 of the rod. The members 169 are resilient and thus it will be understood that the rod ends 161 may be readily inserted between the detents 173 and 174 or may be withdrawn therefrom at will, but that the rod is held by said detents 173 and 174 against accidental detachment.

It should be understood that in the form of 50 the invention illustrated in Figs. 36 to 42 inclusive it is possible to use an ordinary two reach pulley clothes line and that the guard rods 37p may be spaced apart from each other and be located only on those portions of the line where long articles of clothes are hung.

55 While certain preferred embodiments of the invention have been described, it will be understood that certain parts may be used with others and that changes in the form, arrangement, proportions, sizes and details thereof may be made without departing from the scope of the invention as defined in the appended claims.

I claim:

1. The combination with a clothes line having two reaches, namely a clothes carrying reach, and an idle reach, and devices to so support said line that said reaches may travel in opposite directions, of a third reach, means to cause the third reach to travel in the same direction as the 70 clothes carrying reach to prevent the clothes

from lying on and dragging over the idle reach while they are wrapped about the clothes line.

2. The combination with a clothes line having two reaches, namely a clothes carrying reach, and an idle reach, and devices to so support said line that said reaches may travel in opposite directions, of an auxiliary reach to prevent the clothes from lying on and dragging over the idle reach while they are wrapped about the clothes line, means to support said auxiliary reach close to the idle reach and a plurality of devices to keep said reaches properly spaced and from moving towards or away from each other.

3. The combination of a clothes line having a clothes carrying reach, and an idle reach, means to support said line so that said reaches travel in opposite directions, a guard reach close to the idle reach, means to cause the guard reach to travel in the same direction as the clothes carrying reach, said guard reach being effective to prevent the clothes from lying on and dragging over the idle reach, and means whereby all of said reaches may be tightened or slackened at will.

4. The combination of a clothes line having a clothes carrying reach to travel in one direction, and an idle reach to travel in the opposite direction, a guard reach located close to the idle reach and arranged to travel in the same direction as the clothes carrying reach and to prevent the clothes from lying on and dragging over the idle reach, and pulleys to support and guide all of said reaches.

5. In a clothes line the combination of a plurality of pulleys, and a single piece of line supported by said pulleys in a manner to provide four reaches, namely two intermediate reaches and two outer reaches, the intermediate reaches being arranged to travel together in the same direction and in a direction opposite to the direction of travel of the outer reaches, one of the outer reaches serving to carry the clothes, the other outer reach serving as a guard to keep the clothes from lying and dragging on the intermediate reaches when the clothes are wrapped around the clothes line.

6. In a clothes line the combination of a plurality of pulleys, and a single piece of line supported by said pulleys in a manner to provide four reaches, namely two intermediate reaches and two outer reaches, said pulleys being effective to cause the intermediate reaches to travel together in the same direction and in a direction opposite to the direction of travel of the outer reaches, one of the outer reaches serving to carry the clothes, the other outer reach serving as a guard to keep the clothes from lying on and dragging over the intermediate reaches while the clothes are wrapped around the clothes line, and means whereby all of said reaches may be tightened or slackened at will.

7. The combination of a clothes line having three reaches, namely two outer reaches travelling in the same direction, and an intermediate reach travelling in the opposite direction, means to support said reaches for travelling movements, and means adapted to travel with the outer reaches and keep all of said reaches definitely spaced so as to prevent movement thereof towards and away from each other.

8. The combination of a clothes line having three reaches, namely two outer reaches travelling in the same direction, and an intermediate reach travelling in the opposite direction, means to support said reaches for travelling movements,

and a plurality of readily attachable devices adapted to travel with the outer reaches and to keep all of said reaches definitely spaced so as to prevent movement thereof towards and away from each other.

9. The combination of a clothes line having three reaches, namely two outer reaches travelling in the same direction, and an intermediate reach travelling in the opposite direction, means to support said reaches for travelling movements, a detachable device adapted to travel with the outer reaches and keep all of the reaches definitely spaced so as to prevent movement thereof towards and away from each other, and means on said device to prevent accidental detachment thereof from any one of said reaches.

10. The combination with a clothes line having a clothes supporting reach and an idle reach, and means to support said reaches for travelling movements, of a plurality of holders, means on each holder to attach it to the clothes supporting reach of the clothes line, means on each holder to facilitate transit of the holder on the idle reach of the clothes line, the last mentioned means being also effective to space the clothes carrying reach from the idle reach, and guard reach supported by said holders to prevent the clothes, when wrapped around the clothes line, from dragging on the idle reach while the line is being operated, and means on each holder to prevent the guard reach from moving into engagement with the idle reach.

11. The combination of a clothes line having four reaches, namely two outer reaches travelling in the same direction and two intermediate reaches travelling in the same direction but opposite to the direction of travel of the outer reaches, means to support said reaches for travelling movements, a holder, means at the ends of said holder to embrace the outer reaches of the clothes line to keep them definitely spaced from each other, and means on said holder to keep the intermediate reaches definitely spaced from the outer reaches.

12. The combination of a clothes line having a clothes carrying reach, and an idle reach, a guard reach, means to support said reaches for traveling movements, a holder having means to attach it to the clothes carrying reach, means to facilitate freedom of transit of the holder on the idle reach, and means on said holder to support the guard reach to cause it to travel with the clothes supporting reach, the last mentioned means and the third mentioned means cooperating to hold the guard reach definitely spaced from the idle reach.

13. The combination with a clothes line having a clothes carrying reach, and an idle reach, and means to support said reaches, of a guard reach and a holder having means to attach it to the clothes carrying reach, means to facilitate freedom of transit of the holder on the idle reach, means on said holder to support the guard reach, the attaching means, the transit means and the guard supporting means serving to keep the three reaches definitely spaced with respect to each other, and means to prevent accidental detachment of the holder from the clothes line.

14. The combination of a clothes line having three reaches, two of said reaches arranged to travel in the same direction and opposite to the third reach, means to support said reaches for traveling, one of said two reaches serving to carry the clothes, and a holder to travel with said two reaches and hold all of said reaches spaced from

each other, the other one of said two reaches serving to prevent the clothes from lying on or dragging over said third reach.

15. In a clothes line, the combination of a plurality of pulleys, a single piece line supported by said pulleys in a manner to provide four reaches, namely two intermediate reaches and two outer reaches, the intermediate reaches travelling together in the same direction and opposite to the outer reaches, one of the outer reaches being located below the intermediate reaches and serving to carry the clothes, the other outer reach being located above the intermediate reaches and serving as a guard to keep the clothes from lying on the intermediate reaches when the clothes are wrapped around the clothes line, and means to hold the two intermediate reaches together, said means serving also to hold the two outer reaches spaced from each other and from the intermediate reaches.

16. In a clothes line the combination of a plurality of pulleys, a single piece line supported by said pulleys in a manner to provide four reaches, namely two intermediate reaches and two outer reaches, the intermediate reaches travelling together in the same direction and opposite to the outer reaches, one of the outer reaches serving to carry the clothes, the other outer reach serving as a guard to keep the clothes from bearing down on and dragging over the intermediate reaches while the clothes are wrapped around the line, and a plurality of holders, each holder engaging the two outer reaches and travelling therewith, each holder being supported by one of the outer reaches and serving to support all of the other reaches and to keep them definitely spaced with respect to each other.

17. The combination of a clothes line having two reaches, namely a clothes carrying reach and an idle reach, means to support said reaches to travel in opposite directions, and means to travel with the clothes supporting reach to prevent the clothes from lying on the idle reach when the clothes are accidentally wrapped about the clothes line and to prevent the clothes from dragging over the idle reach, said means consisting of two brackets on the clothes supporting reach, and a bar extending from one bracket to the other, said bar being located above said idle reach.

18. The combination of a clothes line having two reaches, namely a clothes carrying reach and an idle reach, means to support said reaches to travel in opposite directions, and means to travel with the clothes supporting reach to prevent the clothes from lying on the idle reach when the clothes are accidentally wrapped about the clothes line and to prevent the clothes from dragging over the idle reach, said means consisting of two brackets on the clothes supporting reach, and a bar extending from one bracket to the other, said bar being located above said idle reach, said bar having two sections to vary the length thereof.

19. The combination of a clothes line having two reaches, namely a clothes carrying reach and an idle reach, means to support said reaches to travel in opposite directions, and means to travel with the clothes supporting reach to prevent the clothes from lying on the idle reach when the clothes are accidentally wrapped about the clothes line and to prevent the clothes from dragging over the idle reach, said means consisting of two brackets on the clothes supporting reach, a bar extending from one bracket to the

other, said bar being located above said idle reach, means to facilitate detachable mounting of said bar on said holders, and means to prevent accidental detachment of the bar from the holders.

5 holders.

20. The combination of a clothes line having two reaches, namely a clothes carrying reach and an idle reach, means to support said reaches to travel in opposite directions, and means to travel with the clothes supporting reach to prevent the clothes from lying on the idle reach when the clothes are accidentally wrapped about the clothes line and to prevent the clothes from dragging over the idle reach, said means consisting of two brackets on the clothes supporting reach, a bar extending from one bracket to the other, said bar being located above said idle reach, means to detachably support said bar on said holders, the bar having a plurality of sections to vary its length, and means to prevent accidental detachment of said bar from said holders.

21. The combination of a clothes line having two reaches, namely a clothes carrying reach and an idle reach, means to support said reaches to travel in opposite directions, and means to travel with the clothes supporting reach to prevent the clothes from lying on the idle reach when the clothes are accidentally wrapped about the clothes line and to prevent the clothes from dragging over the idle reach, said means consisting of a plurality of holders successively arranged on the clothes supporting reach, and a plurality of bars, each bar extending from each one of said holders to the next adjacent holder.

25

30

35

35 case of said holder to the next adjacent holder.

22. A clothes line having at least three co-extensive members namely two outer members, and an intermediate member, means to support said members above each other so that the lower member and the intermediate member travel in opposite directions, and means to cause the upper outer member to travel with and in the same direction as the lower outer member.

40

23. The combination with a pulley clothes line
45 having two substantially parallel reaches, means
to support said reaches that they may travel in
opposite directions, said reaches constituting a
clothes carrying reach and an idle reach, of guard
means located above the idle reach and extending
50 lengthwise thereof to prevent the clothes
from lying on said idle reach, means to hold the
first mentioned means properly spaced from the
idle reach, and means to support said guard
means to cause it to travel with and in the same
55 directions as the clothes carrying reach.

33 directions as the clothes carrying reach.
24. The combination with a pulley clothes line having two reaches, namely a clothes carrying reach and an idle reach, and means to support said reaches to travel in opposite directions of 60 guard means, and means to support the guard means above the idle reach and to cause it to travel with and in the same direction as the clothes carrying reach to thereby prevent the clothes from lying on and dragging over the idle reach.

65 reach.

25. The combination with a pulley clothes line having two reaches namely a clothes carrying reach and an idle reach, and means to support said reaches for movements back and forth and in opposite directions with respect to one another, of guard means, means to support the guard means above the idle reach to thereby prevent the clothes from lying on the idle reach, and means effective in both directions of travel

70

75 of the clothes carrying reach to cause the guard

means to travel in the same direction as the clothes carrying reach.

26. The combination of a pulley clothes line having three substantially parallel elements, namely, a clothes supporting element, an idle element, and a guard element, pulleys to support the clothes supporting element and the idle element for movements in opposite directions, a plurality of holders, means on each holder to hold it on the clothes supporting element substantially at right angles thereto, means on each holder to engage the idle element to keep the holder in a vertical position transversely of the line, and means at the upper end of each holder to support the guard element and hold it against movement towards the idle reach.

27. The combination of a pulley clothes line having three substantially parallel elements, namely, a clothes supporting element, an idle element, and a guard element, pulleys to support the clothes supporting element and the idle element for movements in opposite directions, a plurality of holders, means at the lower end of each holder to engage the clothes supporting element at opposite sides thereof to hold it substantially at right angles thereto, rollers on each holder and at an intermediate position thereof

5 to cooperate with the idle element at opposite sides thereof to space the idle element from the clothes supporting element and to hold the holder in a vertical position transversely of the line, and means at the upper end of each holder to assist in holding the guard element and keep it from moving towards the idle element.

10 28. The combination of a clothes line having a clothes carrying reach, and idle reach, means to support said line so that said reaches travel in opposite directions, a guard reach close to the idle reach, means to cause the guard reach to travel in the same direction as the clothes carrying reach, said guard reach being effective to prevent the clothes from lying on and dragging over the idle reach, means whereby all of said reaches may be tightened or slackened at will, and a holder to keep said reaches definitely spaced, said holder including means to attach it to the clothes carrying reach and cause it to travel therewith, means to facilitate freedom of transit on the idle reach, and means to engage the guard reach, the last mentioned means permitting a longitudinal movement of the guard reach relatively to said holder during a tightening or slackening operation of said reaches.

20 25 JOHN WALDHEIM.
